[57] CLAIM

The ornamental design for a bicycle trailer body, as shown and described.

DESCRIPTION

FIG. 1 is a side elevational view of a bicycle trailer body showing my new design, the opposite side being a mirror image of that side shown;

FIG. 2 is a front elevational view thereof;

FIG. 3 is a top plan view thereof; and,

FIG. 4 is a bottom plan view thereof.

The broken lines shown in all drawing views are for illustrative purposes only and from no part of the claimed design.
